UNITED STATES PATENT OFFICE.

GEORGES A. BROUILLET, OF BROOKLINE, MASSACHUSETTS.

ARTIFICIAL TOOTH.

1,281,500.

Specification of Letters Patent.

Patented Oct. 15, 1918.

Application filed May 27, 1916. Serial No. 100,365.

To all whom it may concern:

Be it known that I, GEORGES A. BROUILLET, a subject of the King of Great Britain, residing at Brookline, county of Norfolk, State 5 of Massachusetts, have invented an Improvement in Artificial Teeth, of which the following description, in connection with the accompanying drawing, is a specification, like characters on the drawing representing 10 ing like parts.

This invention relates to artificial teeth and has for its main object to provide an improved artificial tooth and an improved way of inexpensively but effectually securing 15 said tooth to a bridge, crown or other support.

Other objects of the invention are to provide an artificial tooth construction in which the metallic backing is entirely concealed 20 from view so that the tooth has all the appearance of a natural tooth, and also to provide a novel construction by which an artificial tooth can be readily replaced by another tooth without removing the bridge, 25 crown or other support from the mouth, and which has other advantages, all as will be more fully hereinafter set forth. A tooth embodying my invention may be made of porcelain or any other suitable material and 30 is formed with a nub or protuberance at its base which presents an anchoring rib on its sides and bottom and which also is provided with a cement-receiving cavity in the rear 35 face of the protuberance or nub. This tooth thus made is secured to a holding member, preferably made of metal, and which is fixedly secured to the bridge, crown, or other support. This holding member has a shape 40 to fit the protuberance or nub, and a lip to embrace the anchoring rib on the nub. The holding member is also provided with a cement-receiving pocket which communicates with the pocket of the tooth when the tooth is properly positioned in the holding 45 member. The tooth is secured to the holding member by cement which fills the pockets in the tooth and holder, respectively, said cement forming a sort of anchoring member to tie the tooth to the holding member 50 and to resist the strains due to occlusion. The shape of the holding member and the protuberance on the tooth is such that

the tooth can be placed into or removed from the holding member by a vertical movement. In an artificial tooth embodying my invention the metal of the holding member is situated entirely at the base of the tooth and, therefore, is not visible. The construction of the tooth and holding member is such that a tooth can be readily placed into 55 or removed from the holding member, thus making it possible to replace an injured tooth without removing the bridge or crown work from the mouth.

The invention is also applicable to all the 60 different varieties of teeth and is thus universal in its adaptation.

In order to give an understanding of the invention I have illustrated in the drawings a selected embodiment thereof which will 65 now be described, after which the novel features will be pointed out in the appended claims.

Figure 1 is a vertical sectional view through an artificial tooth embodying my 70 invention, said figure showing the tooth attached to the bridge;

Fig. 2 is a vertical section through the tooth;

Fig. 3 is a vertical section through the 80 tooth showing the holding member shaped to fit the tooth;

Fig. 4 is a perspective view of the holding member;

Figs. 5 and 6 are sectional views of the 85 holding member showing different steps in the process of attacking the tooth;

Fig. 7 is a perspective view of the completed holding member;

Fig. 8 is a side view of the tooth; 90

Fig. 9 is a rear view thereof.

In the drawings 1 indicates the metal support to which the artificial tooth is to be secured. This support may be a bridge, a crown, or any other similar element commonly used in dentistry as a support for 95 artificial teeth.

2 indicates an artificial tooth which may be made of porcelain or any other suitable material and which is to be secured to the 100 supporting member 1. The tooth shown in the drawings is one of the front teeth, but the invention is equally applicable for use in securing bicuspids, molars or other teeth to

bridges or crowns. The tooth 2 is a complete tooth and not simply a porcelain facing, said tooth having the complete shape of a tooth and having sufficient strength to resist the strains of occlusion. The tooth is formed at its base with an extension or protuberance 3 which is shaped to present on its sides and bottom an anchoring rib 9. This rib terminates at 16 near the upper end of 10 the sides of the protuberance. The tooth is also provided with a pocket or cavity 6 formed in the rear face 7 of the protuberance 3, said pocket preferably being larger at its bottom than at the face 7 for reasons pres- 15 ently to be described.

The tooth thus made is secured to the supporting member 1 by means of a holding member 8 shown best in Figs. 6 and 7. This holding member is made from thin 20 sheet metal and is of a shape to fit the face 7 and rib 9 of the protuberance 3, said holding member having the lip 10 which embraces the rib 9, this lip extending nearly to the top of the holding member, as shown 25 in Fig. 4. The holding element is also provided with a cement-receiving pocket 14 which is preferably larger at its bottom than at the open end thereof, said pocket being so situated that when the tooth is in 30 the holding member, the pocket 14 will be in communication with the pocket 6 of the tooth. The shape of the lip 10 and of the rib 9 is such that the tooth can be placed in the holding member by a downward and inward movement and can be removed from the holding member by an upward and outward movement. The holding member is permanently and rigidly secured to the support 1 in any suitable way as by being 35 soldered thereto, and after the holding member is thus secured to the support the tooth may be slipped into said member by a downward movement. The tooth is permanently secured to the holding member by 40 means of cement 15 which fills the communicating pockets 14 and 6, it being understood, of course, that the contacting surfaces of the tooth and the holding member will also be provided with a coating of cement. 45 The interlocking of the rib 9 of the protuberance 3 and the lip 10 of the holding member will prevent the tooth 2 from being removed laterally from the holding member. The cement 15 which serves to tie the 50 tooth to the holding member will prevent any vertical movement of the tooth relative to the holding member and by reason of the special shape of the pockets 14 and 6, said cement will also assist in preventing the 55 lateral movement of the tooth relative to the holding member. The strains of occlusion are resisted by the cement 15. The pocket 14 in the holding member 8 may be made in any suitable way. As herein illustrated, 60 the holding member 8 is formed with an in-

dented portion 11 opposite the pocket 6 at the time that said member is shaped to the protuberance 3, as shown in Figs. 3 and 4. A sheet or plate 12 is then soldered to the outer face of the holding member over the 70 indented portion 11, as shown in Fig. 5, and the material at the extremity of the indented portion is then removed, as shown in Fig. 6, thereby forming a pocket which is larger at the base than at the opening. It will be 75 noted that the holding member 8 is co-extensive with the protuberance 3 only and none of the metal will be visible when the tooth is in place. An artificial tooth embodying my invention, therefore, will have 80 the appearance of a natural tooth.

My invention has the further advantage that if for any reason the artificial tooth becomes injured and needs to be replaced, this operation can be performed without removing the bridge or other support from the mouth for the defective tooth can be easily taken out from the holding member 8 and a new tooth inserted while the support 1 is still in the mouth. The shape and construction of the holding member is such that a tooth is firmly held thereby and in such a way as to effectually resist all strains due to occlusion. Further, the construction is comparatively inexpensive. 95

Another advantage of my invention is that the tooth herein shown is well adapted for use in casting or forming plates of false teeth, for when the rubber, celluloid or other material used for the plate is cast about the 100 protuberance 3 and fills the pocket 6, the tooth will be firmly anchored and secured to the plate without the use of pins or rivets usually employed for this purpose. The tooth is, therefore, universal in its adaptation, and the use of my improved tooth obviates the necessity of having one variety of artificial tooth for crowns and bridge work and another variety for use in making dentures. 110

I claim:

1. The combination with a tooth-supporting member, of a complete tooth having at its base a protuberance or extension shaped to present an anchoring rib on its sides and bottom and provided with a pocket in its rear face, and a holding member permanently secured to the supporting member and provided with a lip to embrace said anchoring rib and with a cement-receiving pocket 115 which communicates with the pocket of the tooth when the tooth is in position, and cement filling the communicating pockets and thus securing the tooth and holding member together. 120

2. The process of making artificial teeth which consists in providing a porcelain tooth having at its base a protuberance provided on its sides and bottom with an anchoring rib and provided in its rear face 130

with a cement-receiving pocket, forming a metal holding member to fit said protuberance and embrace the anchoring rib there-of and provided with a cement-receiving 5 pocket which is situated to communicate with the pocket of the tooth when the tooth and holding member are in operative relation, and then placing the protuberance of

the tooth into the holding member and securing the tooth to the holding member by 10 cement which fills the communicating pockets.

In testimony whereof, I have signed my name to this specification.

G. A. BROUILLET.
